US00D971914S

(12) **United States Design Patent** (10) **Patent No.:** **US D971,914 S**
Wang (45) **Date of Patent:** **** Dec. 6, 2022**

(54) **SMART WATCH**

(71) Applicant: **Andon Health Co., Ltd.**, Tianjin (CN)

(72) Inventor: **Yong Wang**, Tianjin (CN)

(73) Assignee: **Andon Health Co., Ltd.**, Tianjin (CN)

(**) Term: **15 Years**

(21) Appl. No.: **29/763,897**

(22) Filed: **Dec. 25, 2020**

(30) **Foreign Application Priority Data**

Sep. 24, 2020 (CN) 202030572923.0

CLAIM

The ornamental design for a smart watch, as shown and described.

DESCRIPTION

FIG. 1 is a front perspective view of a smart watch showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a bottom plan view thereof, with the top plan view being a minor image thereof.

1 Claim, 5 Drawing Sheets
